NONREFILLABLE CONTAINER

Filed July 15, 1935

UNITED STATES PATENT OFFICE

2,054,722

NONREFILLABLE CONTAINER

Walter Y. Cobb, Jacksonville, Fla.

Application July 15, 1935, Serial No. 31,505

2 Claims. (Cl. 220—86)

This invention relates to a non-refillable container of drum-like-form and has for its object to provide, in a manner as hereinafter set forth, a container of the class referred to with new and novel means at its filling and discharge points to prevent the refilling of the container after the contents of the latter have been discharged.

Further objects of the invention are to provide, in a manner as hereinafter set forth, a container of the class referred to which is simple in its construction and arrangement, strong, durable, compact, thoroughly efficient for the purpose intended thereby, readily assembled and comparatively inexpensive to manufacture.

With the foregoing and other objects in view, the invention consists of the novel construction, combination and arrangement of parts as will be hereinafter specifically described and as illustrated in the accompanying drawing, wherein is shown an embodiment of the invention, but it is to be understood that changes, variations and modifications may be resorted to which fall within the scope of the invention as claimed.

In the drawing:

Figure 1 is a side elevation of the container broken away at its filling and discharge points.

Figure 2 is a vertical sectional view of a closeable intake element, in open position for the bung-hole or filling opening of the container.

Figure 3 is a vertical sectional view of the closeable intake element, in closed position for the bung-hole or filling opening of the container.

Figure 4 is a section on line 4—4, Figure 2.

Figure 5 is a section on line 5—5, Figure 3.

Figure 6 is a vertical sectional view of a valve controlled element for the discharge opening of the container, and

Figure 7 is a section on line 7—7, Figure 6.

The drum indicated at 1 is formed of sheet metal and its body 8, preferably at its center, is provided with a bung-hole or filling opening 9. The drum 1 is also provided in one of its heads 10 with a discharge opening 11 in close proximity to body 8. The heads 10 are inset with respect to the ends of body 8.

Welded to or otherwise secured to the wall of bung-hole 9 and extending into body 8 is the outer end of a closable and lockable intake element 12 for body 8. The element 12 includes an outer stationary cylinder 13 having a closed inner end or bottom 14, an open outer end 15 and a circumferentially extending opening 16 spaced from the ends 14, 15. The side edges 17 of opening 16 are squared. The inner face of cylinder 13, at the upper portion thereof, is threaded as

at 18. The upper face of the closed inner end 14 of cylinder 13 is provided with an eccentrically disposed pocket 19. The end or bottom 14 is of greater thickness than the body of the cylinder and it is formed with an axial opening 20. The element 12 also includes an inner revoluble cylinder 21, mounted in, of less height than and of an outer diameter to provide a tight fit against the inner face of cylinder 13. The fit is such, however, to enable the revolving of cylinder 21 relative to cylinder 13 by the use of a tool. The cylinder 21 has an open upper end 22, a closed bottom 23 and a circumferentially extending opening 24 spaced at its top from its upper end 22 and having its bottom wall provided by bottom 23. The opening 24 is of the same area as opening 16. The side walls 24^a of opening 24 are squared. The upper end 22 of cylinder 21 is notched, as at 24^b, to receive a tool for revolving it in a direction to have a part of the body thereof to close opening 16. Normally the walls of opening 24 register with the walls of opening 16 to form a passage as shown in Figures 2 and 4 to enable the filling of the container. After the container has been filled to the extent desired, the cylinder 21 is revolved to the position shown in Figures 3 and 5 to close element 12. The bottom 23 is of greater thickness than that of the body of cylinder 21 and also than that of the inner end of bottom 14 of cylinder 13. The lower face of bottom 23 of cylinder 21 has an eccentrically disposed pocket 25 carrying a spring controlled locking member 26 which bears against the upper face of bottom 14 of cylinder 13 and is of greater thickness than the depth of pocket 19. The controlling spring for member 26 is indicated at 27 and is interposed between member 26 and the base of pocket 25. When cylinder 21 is shifted from the position shown in Figures 2 and 3, the member 26 rides against the upper face of bottom 14 until pockets 19, 25 register, at this point member 26 drops into and extends above pocket 19 as shown in Figure 3. When member 26 is in the position shown in Figure 3, it coats with the walls of pockets 19, 25 and locks the cylinders 13, 21 together, in the position shown in Figures 3 and 5 to close the passage for the purpose of preventing the shifting of the cylinders relatively to each other to open element 12 to prevent refilling. The bottom 23 is formed with an axial opening 28 which aligns with opening 20. A pivot 29 extends through aligning openings 20, 28 and is headed, as at 30 at each end whereby the cylinders 13, 21 are connected together, but at the same time permitting cylinder 21 being revolved relative to cylinder 13 when the

cylinders are not locked together by member 26. A peripherally threaded closure plug, cap or disc, not shown is employed for closing the outer end of cylinder 13 and which is to threadedly engage 5 with the threads 18. This cap, disc or plug is to be of known construction.

Welded or otherwise secured to the wall of opening 11, as well as extending inwardly into body 8 is a valve controlled element or structure 31 10 which functions to permit of the discharge of the contents and to prevent the refilling of the drum from the discharge opening thereof. The element 31 includes a cylinder 32 open at each end and formed at its outer end with an inwardly extending 15 annular flange 33 having its free edge threaded, as at 34. The cylinder 32 at the inner end of its inner face is rabbeted, as at 35, and has also formed integral with its inner face a series of spaced radially disposed ribs 36 positioned adjacent to and in spaced relation with respect to the inner face of flange 33. The ribs 36 merge into the edge of an arrestor 37 in the form of a disc having a concaved rear face 37a. The ribs 36 have their inner ends curved, as at 37b and with 20 the arc forming a flush continuation of the face 37a of arrestor 37. The face of arrestor 37 and rear ends of ribs constitute a stop for arresting the outward movement of a floating ball valve 38 arranged within and of less diameter than the inner diameter of cylinder 32. The ribs 36 are of 25 a length to have their rear ends positioned at a point forwardly of the transverse median of cylinder 32. The forward end of ribs 36 are of the same width as that of the body of flange 33. 30 Seated against the edges of the rabbet 35 and against the rear end edge 40 of cylinder 32 is an annulus 41 formed with a flange 42 on its outer edge 43. The flange 42 seats against edge 40. The outer edge 43 of annulus 41 bears against the 35 longitudinally disposed edge of the rabbet 35. The inner or forward face of annulus 41 bears against the horizontally disposed edge of the rabbet 35. The annulus 41 extends across the inner end of cylinder 32 and is welded or otherwise secured to the latter. The inner diameter of annulus 41 is less than the diameter of the floating ball valve 38 and has its inner edge beveled, as at 44, to provide a seat for floating ball valve 38. There is associated with the cylinder 32 a peripherally threaded closure cap, plug or disc 45 for 40 normally closing element 31 when filling the drum through element 12. The cap, plug or disc 45 is 45

removed when the contents of the container are to be discharged. This cap, plug or disc 45 detachably engages the threads of flange 33. The threads 34 of the flange 33 are also employed for connecting a discharge pipe 46 to element 31 when 5 cap 45 is removed. The floating ball valve 38 when abutting its seat prevents the refilling of the drum or container through element 31. The ribs 36 arrest the opening movement of the floating ball valve 38 and when the latter is off its seat, 10 the contents of the container pass around the floating ball valve 38, around the edge of arrestor 37 and over the outer ends of ribs 36. The arrestor 37 in connection with the ribs 36 prevents the entrance of a wire or other means for the purpose of holding the floating valve 38 off its seat 15 to permit of the refilling of the container.

What I claim is:

1. A non-refillable container comprising a headed drum like body formed with a bung-hole, 20 an intake element anchored to the wall of the bung-hole, extending into said body and having a normally open intake passage for permitting of the initial filling of the drum, said element having interiorly arranged coacting parts for closing 25 said passage and means for locking said coacting parts in passage closing position to prevent the refilling of the drum after the initial filling has been completed, the said locking means of said element consisting of a stationary pocket, a shiftable 30 pocket for register with the stationary pocket, and a locking member carried by the shiftable pocket for extension into the stationary pocket when the pockets are in registry.

2. A non-refillable container comprising a 35 headed drum like body formed with a bung-hole, an intake element anchored to the wall of the bung-hole, extending into said body and having a normally open intake passage for permitting of the initial filling of the drum, said element having 40 interiorly arranged coacting parts for closing said passage and means for locking said coacting parts in passage closing position to prevent the refilling of the drum after the initial filling has been completed, the said coacting parts consisting of a pair 45 of concentrically arranged cylinders formed with openings for registry to form said passage, said cylinders being open at their outer ends, one of said cylinders being revoluble relative to the other for moving a part thereof to close the opening in 50 the other cylinder.

WALTER Y. COBB.
